COMBINED AUXILIARY STOP LIGHT AND ORNAMENT FOR AUTOMOTIVE VEHICLES

Wilbur Neuenschwander, 120 N. Main St.,
Bluffton, Ohio

Filed Oct. 2, 1961, Ser. No. 66,922

Term of patent 14 years

(Cl. D48—32)

Fig-1

Fig-2

Fig-3

Fig-4

Fig-5

FIGURE 1 is a side elevation of a combined auxiliary stop light and ornament for automotive vehicles showing my new design;

I claim:

The ornamental design for a combined auxiliary stop light and ornament for automotive vehicles, substantially as shown.
